Specification of Letters Patent.

Patented Dec. 7, 1915.

Application filed June 29, 1914. Serial No. 847,910.

To all whom it may concern:

Be it known that I, STANLEY F. SAWYER, a citizen of the United States, and a resident of Toledo, in the county of Lucas and State of Ohio, have invented a certain new and useful Article of Furniture; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to furniture, and particularly to porch swings, or the like, but is not restricted to such use as it may be used in any connection for which it may be adapted or appropriate.

20 The object of my invention is the provision of a simple and efficient swing of the character described, which may be easily and quickly converted from a seat into a crib, or vice versa, thus enhancing the practicability and commercial value thereof and enlarging its scope of usefulness.

A further object of my invention is the provision of an article of this character, which is simple and inexpensive in its construction, and capable of being used either as a stationary or a swinging settee or seat, the legs thereof being foldable thereunder when suspending for use as a swing.

25 A further object of the invention is the provision, in combination with a swing of this character, of means for enabling the same to be suspended from a single pair of chains or suspending members, and which prevents a tipping over of the swing when in use, such means being adjustable to vary the normal inclination from front to back of the swing.

30 Further objects and advantages of the invention will be apparent from the following detailed description thereof.

The invention is fully described in the following specification, and while, in its broader aspect, it is capable of embodiment in numerous forms, a preferred embodiment 35 thereof is illustrated in the accompanying drawings, in which,—

Figure 1 is a perspective view of the invention in use as a swing. Fig. 2 is a front

elevation thereof in use as a settee with parts broken away and in section. Figs. 3 55 and 4 are cross-sections on the line y , y in Fig. 5 with the legs unfolded, and with the former in the form of a settee and the latter in the form of a crib. Fig. 5 is a central longitudinal section on the line x , x in Fig. 3 60 with the legs folded, and Fig. 6 is a perspective view of one of the end members of the swing.

Referring to the drawings, 1 and 2, respectively, designate the front and back longitudinally extending frame beams of the article, which beams are connected near the ends thereof with cross-beams or members 3. A back 4 rigidly rises from the rear beam 2 and arms 5, 5 connect the back 4 to the forward ends of the respective cross members 3, 3 or to the respective end portions of the front beam 1 as desired. It is preferable to secure the back 4 and the arms 5, 5 to the seat frame in a detachable manner to facilitate a compact packing of the seat for the purpose of shipping or storage.

6 designates a facing strip for the front beam 1 of the seat frame.

Each end of the seat frame is preferably 80 provided with a pair of rigidly connected legs 7, each pair being hingedly connected to the respective end of the seat frame, as shown at 8, for folding movements longitudinally thereunder. A pair of brace bars 85 9, 9 are hingedly connected to and project in opposite directions from a cross piece 10, which connects the frame members 1 and 2 centrally of their ends, the outer ends of said bars being intended to have shoultered 90 engagement with cross-pins 11 of the respective pairs of legs to retain such legs in set-up position, as shown in Fig. 2. Both the brace-bars 9 and legs 7 are intended to fold flat against the under side of the seat frame 95 when the seat is being used as a swing, or when packed for shipping or storage. When the legs 7 are folded under the seat frame they are hid from view at the front of the seat by the facing strip 6, which extends a 100 suitable distance below the front frame-beam 1 for such purpose.

The seat bottom 12 is hinged, in the present instance, to the rear frame-beam 2, as at 13, and has its rear edge rabbeted into the 105 front edge portion of the back frame beam,

so that its top surface is substantially flush with the top edge of such beam and the end frame members 3, 3. The top portion of the front frame beam 1 is cut down between the 5 end members 3, 3 to permit the front edge portion of the seat bottom 12 to rest thereon below the top edges of the end members 3, 3 and the front facing strip 6, as best shown in Figs. 3 and 4. The front edge of 10 the seat bottom 12 terminates short of the facing strip 6 to provide a spacing therebetween.

The part which forms the crib front when the seat is being used as a crib is designated 14, and is of suitable depth to extend from 15 the lowered top surfaces of the front beam 1 to the under sides of the front end portions of the arm rests 5, as shown in Figs. 2 and 4. The lower edge of the crib front 14 is made approximately square by a strip 15 at such edge, such strip being secured to 20 and projecting forwardly from the lower edge of the crib front. The lower edge of the crib front, with the strip 15, is intended to fit into and fill the space between the 25 front edge of the seat bottom and the facing strip 6, so that the seat bottom when in lowered position coöperates at its front edge with the strip 6 to maintain the crib front 14 in its upright position, as shown in Fig. 4. The front end portions of the arms 5 are projected inwardly from the post portions 30 of the arms to permit the top edge of the crib front 14 at the ends thereof to have contact therewith when such front is in upright 35 position. This coaction of the arms and crib front prevents a forward tilting of the front from upright position, but permits a rearward tilting of such front due to the 40 lower front edge portion of the front being disposed in advance of the upright or body portion of such front. When it is desired to change from a crib to a seat, the seat bottom 12 is raised and the crib front 14 swung 45 rearwardly to reclining position, and the seat bottom then lowered thereon with its front edge resting on the body portion of the front adjacent to the strip 15. When 50 the parts are in this position the strip 15 extends upward from the reclining front and fills the space between the front edge of the seat bottom and the facing strip 6, as shown in Fig. 3. The rear edge of the front piece 14 when in reclining position 55 rests on the cross member 10 of the seat frame.

When the seat is to be used as a swing a single suspending chain or member 16 is attached to the upper end of an upright bar 60 17, which is provided at each end of the seat frame in substantially central position transversely thereof. Each bar 17 is carried by an end member 18, which is disposed between the adjacent ends of the front and 65 rear frame beams 1 and 2, and has end por-

tions projected under and secured to such beams, as by screws 19, or in any other suitable manner. The points of attaching of the suspending members 16 to the respective bars 17 are disposed above the plane of the 70 seat bottom, substantially as shown, as with such arrangement it is found that when weight is applied to the seat it is impossible to tip the same completely over. In order to permit a varying of the normal inclination of the seat bottom when the seat is in suspended position the bars 17 are adjustably attached to the respective end members 18, being pivoted at their lower ends to such members, as at 20, to facilitate a transverse 80 swinging of the bars relative to the seat frame, and having their upper ends adjustably attached to the upper portion of the respective members 18 by bolts 21 extending through any one of a plurality of holes 22 85 in the members, as shown, or such adjustment may be accomplished in any other suitable manner. It is preferable to removably attach the end members 18 to the seat frame to enable such end members and the bars 17 90 to be removed from the frame when it is being used as a stationary settee.

It is evident that I have provided a simple and efficient article of furniture, which may be used either as a swinging seat or a stationary seat and when used as a swinging seat may have its supporting legs folded in closed position thereunder, and which is also provided with simple and efficient means for enabling it to be easily and quickly converted from a seat to a crib, and vice versa, the crib front being disposed in inconspicuous position within the seat when in use.

I wish it understood that my invention is not limited to any specific construction, arrangement or form of the parts, as it is capable of numerous modifications without departing from the spirit of the invention.

Having thus described my invention, what I claim as new, and desire to secure by Letters Patent, is—

1. In a seat, a frame, a seat bottom and a crib front each movably carried by said frame and foldable one over the other when the crib front is in inoperative position, 115 said seat bottom and frame coöperating to secure the crib front in operative position.

2. In a seat, a frame, a seat bottom and a crib front each movably carried by the frame, the said front being disposed in reclining 120 position under the seat bottom when not in use, and the seat bottom and frame coöperating to hold the crib front in upright position when in use.

3. In a seat, a frame, a seat movably carried by said frame and having its front edge spaced from the front edge portion of the frame, and a crib front having its lower edge mounted in and filling such space, both 125 when in operative and inoperative positions,

said seat bottom coöperating with the frame to secure the crib front in either operative or inoperative positions.

4. In a seat, a frame, a seat bottom movably carried by said frame and having its front edge spaced from the front edge portion of said frame, a crib front movably carried by said frame and adapted to stand in upright operative position or in reclining inoperative position relative to the frame, said crib front when in inoperative position being disposed under the seat bottom and having its lower edge portion filling the space between the said bottom and the front edge portion of the frame, both when in operative and inoperative positions.

5. In a seat, a frame, a seat bottom movably carried by said frame and having its front edge spaced from the front edge portion of the frame, a crib front having its lower edge forwardly broadened and adapted to fit in and close said space when said front is in reclining position under the seat bottom or in upright position relative thereto, said seat bottom and frame coöperating to hold the crib front in either reclining or upright positions.

6. In a seat, a frame, a seat bottom, a crib front, and arms, said seat bottom and frame coöperating to hold the lower edge of the crib front in set-up position and the arms

coacting with the upper portion of the crib front to assist the seat bottom and frame in holding the crib front in set-up position.

7. In a seat, a frame, a seat bottom, a movable crib front and arms, said seat bottom and frame coöperating to form a groove adjacent to the front edge portion of the frame for receiving the lower edge of the crib front, and said arms coacting with the upper edge of the seat frame to assist said seat bottom and frame in releasably holding the crib front in set-up position.

8. In a seat, a frame, arms carried by said frame and having inwardly projecting ledge portions, a seat bottom and a crib front, each movably carried by the frame, said seat bottom and frame coöperating to form a recess in which the lower edge of the crib front closely fits and said arm ledges overhanging and coacting at their under sides with the upper edge of the crib front to hold said front in the said recess and coöperating with said bottom and frame to hold the crib front in set-up position.

In testimony whereof, I have hereunto signed my name to this specification in the presence of two subscribing witnesses.

STANLEY F. SAWYER.
